UNITED STATES PATENT OFFICE.

RUDOLPH J. LANGER, OF MONTICELLO, IOWA, ASSIGNOR, BY MESNE ASSIGNMENTS, TO FRANKLIN EQUIPMENT COMPANY, OF MONTICELLO, IOWA, A CORPORATION OF IOWA.

STOP BAR.

Application filed November 21, 1925. Serial No. 70,452.

The present invention relates in general to the care of live stock and more particularly to a stop bar attachment for stalls, which embodies novel features of construction, whereby it can be readily mounted in position and will operate in an effective manner to close the space between the stall post and the stanchion when the latter is opened, and prevent the cow from putting her head 10 in the wrong place.

A further object of the invention is to provide a stop bar attachment in which the stop lug or member is independent of the pivotal connection with the shift bar, so as to avoid the trouble which might otherwise be caused by the bending of the bolts at the pivotal connections when the cows push hard against the stop bars.

The invention also contemplates a stop bar attachment which can be connected to the stall any time after the stall is in the cement, which has positive upper and lower stops to prevent twisting of the stop bar by pressure of the cow against the same, and which has a single lock member for holding the stop bar in either an open or a closed position.

One particular embodiment of the invention will be shown and described in detail for illustrative purposes although it will be understood that many modifications and changes can be made in the details of construction without departing from the spirit of the invention.

For a full understanding of the invention reference is to be had to the following description and accompanying drawings, in which,

Figure 1 is a front elevation of one side of the conventional stall with the stop bar attachment applied thereto and shown in a closed position, portions being broken away and one side of the stanchion being indicated by dotted lines.

Figure 2 is a stop plan view of the stop bar attachment and adjacent parts of the stall, the stop bar being in a closed position.

Figure 3 is a similar view showing the positions assumed by the parts when the stop bar is in an open position.

Figure 4 is an enlarged transverse sectional view on the line 4—4 of Figure 1, looking in the direction of the arrows.

Figure 5 is an enlarged top plan view of

the bracket upon which the lower swinging arm is pivotally mounted.

Figure 6 is an enlarged top plan view of the lower swinging arm, the stop bar being shown in section.

Corresponding and like parts are referred to in the following description and indicated on all of the views of the drawing by like reference characters.

Referring to the drawings, the numeral 1 designates a conventional stall post which is connected at its upper end to a horizontal top rail 2. There is ordinarily a post 1 at each side of the stall and a stanchion such as that indicated by dotted lines at 3 is suspended from the top rail 2 at an intermediate point between the stall posts. When the stanchion is open there is a considerable space between the closed side thereof and the adjacent stall post, and in order to prevent the cow from putting her head in this space instead of in the stanchion, a stop bar is frequently used. After the cow has been secured in the stanchion it is desirable to swing the stop bar back against the stall partition, as indicated by Figure 3. The stop bar is thus moved out of the way of the cow and the cow can turn her head both ways, card herself on either side and lie naturally.

The stop bar 4 is carried by upper and lower swinging arms 5 and 6, respectively, which have a similar construction. Each of the swinging arms is provided at its inner end with a pivot opening 7, and the pivot opening of the lower swinging arm receives a pivot pin 8 on a bracket 9. The bracket 9 projects laterally from the lower portion of the stall post 1 and is provided at one end thereof with a divided clamp 10, by means of which it is securely fastened to the stall post. The bracket is formed with an extension 9^a which projects beyond the pivot pin 8 and is slightly off-set laterally, being provided with a stop lug 11 which engages the swinging arm 6 to limit the movement thereof when the stop bar is in operative position, as shown by Figure 1.

The pivot opening 7 at the inner end of the upper swinging arm 5 receives a downwardly projecting pivot pin 12 on a divided clamping collar 13 which is securely fastened to the top rail 2. The clamping collar is arranged on the top rail so that the upper pivot pin 12 is directly over the lower

pivot pin 8, thereby providing a pivotal mounting for the stop bar which enables the same to be readily swung either into or out of operative position.

- 5 The upper swinging arm 5 is formed with an upwardly projecting stop lug 14, having a curved seat 14^a at the upper end thereof which is adapted to engage the top rail 2 when the stop bar is in a closed position.
- 10 A wing 15 projects laterally from the stop lug 14 and has an opening therein which loosely receives a pivot pin 16 projecting from a lateral neck 17 on a sleeve 18. A nut 19 may be applied to the stem 16 to prevent withdrawal of the stem from the opening. A shift bar 20 is received within the sleeve 18 and securely fastened thereto, said shift bar extending along the top rail in a substantially parallel relation thereto.
- 15 20 There are usually several stalls in a row and the shift bar 20 is intended to extend along the top rail of all of the stalls and be connected to the stop bar for each stall, so that all of the stop bars can be simultaneously moved into an open position or a closed position. The clamping collar 13 is formed at the top thereof with pivot lugs 22 connected by a pivot pin 23, upon which a hooked latch member 24 is mounted, said
- 25 30 latch member being adapted to engage the shift bar 20 to hold the stop bar in either an open position or a closed position. In this connection it will be noted that the pivotal or swivel connection between the shift bar and the swinging arm 5 is off-set laterally from the swinging arm and arranged at such a distance from the pivotal connection of the swinging arm that the shift bar 20 is the same distance from the top rail 2 when the stop bar is in an open position or a closed position, and in moving the stop bar from one position to the other position the shift bar is moved away from the top rail. With this arrangement it will be obvious
- 35 40 45 that the same latch member 24 can be used to lock the stop bar in either an open position or a closed position. As shown in Figures 1 and 2 the latch member 24 is engaging the shift bar 20 to lock the stop bar in a closed position, while as shown by Figure 3, the latch member is engaging the shift bar to lock the stop bar in an open position.

50 This simplifies the construction and avoids the necessity of providing two latch members. There is a positive stop at both the upper and lower ends of the stop bar for limiting the rearward movement thereof so that pressure of the animal against one end of the stop bar will not bend and twist the same. Furthermore, the stop means for limiting the movement of the bar is independent of the pivotal or swivel connection between the shift bar and the stop bar, so that there is no danger of this pivotal connection being bent or distorted by a heavy

pressure of the animals against the stop bar. The stop bar can be quickly moved into either an open position or a closed position and when in the latter position tends to prevent the cow from putting her head in the wrong space and make it more probable that the cow will put her head through the open stanchion in the desired manner.

Having thus described my invention, what I claim as new and desire to secure by Letters Patent is:

1. A stop bar attachment for stalls having stall posts and a top rail, upper and lower swinging arms, a support from the top rail for the upper arm, a stop bar mounted upon said arms, a stop lug projecting from the upper swinging arm and disposed to engage said rail to limit the swinging movement of the stop bar, a shift bar pivotally mounted upon said stop lug, a lateral bracket projecting from a stall post upon which bracket the lower arm is pivoted, and a stop on said bracket to engage the lower arm.

2. A stop bar attachment for stalls, including a stop bar, swinging arms carrying the stop bar, a stop lug projecting from one of the swinging arms and adapted to engage a stall part to limit the swinging movement of the stop bar, a shift bar, and a pivotal connection between the shift bar and the stop lug, whereby the stop bar can be moved into and out of operative position by means of the shift bar.

3. A stop bar attachment for stalls, including a stop bar, swinging arms carrying the same, a stop lug projecting from one of the swinging arms and adapted to engage a stall part to limit the swinging movement of the stop bar, a shift bar, a pivotal connection between the shift bar and the stop lug, and a latch member engaging the shift bar to lock the stop bar in shifted position.

4. A stop bar attachment for stalls having a top rail, including a stop bar, a clamp applied to the top rail, a swinging arm pivotally mounted on the clamp and connected to the upper end of the stop bar, a shift bar extending parallel to the top rail of the stall, a lug projecting from the swinging arm, means for pivotally connecting the shift bar to the lug in an off-set relation to the arm and at such a distance from the pivot center of the arm that the shift bar will be the same distance from the top rail when the stop bar is in either an open or a closed position, and a latch member mounted upon the rail for engaging the shift bar to lock the stop bar in either an open or a closed position.

5. A stop bar attachment for stalls having a top rail including a stop bar, a clamp applied to the top rail, a swinging arm pivotally mounted upon the clamp and connected to the stop bar, a stop lug projecting from the swinging arm and adapted to engage the top rail to limit the swinging movement of the

stop bar, a lateral wing projecting from the stop lug, a shift bar, a pivotal connection between the shift bar and the lateral wing, said pivotal connection being off-set from the swinging arm so that the shift bar is the same distance from the top rail when the stop bar is in either an open or a closed position, and a latch member mounted upon the clamp and adapted to engage the shift bar to lock the stop bar in either an open or a closed position.

6. A stop bar attachment for stalls having a stall post and a top rail, including a lateral bracket adapted to be secured to the stall post, a stop bar, upper and lower swinging arms carrying the stop bar, the lower swinging arm being pivotally mounted on the lateral bracket, a pivotal mounting for the upper swinging arm, a stop means on the lateral bracket for limiting the swinging movement of the lower arm when the stop bar is in operative position, and a stop lug projecting from the upper swinging arm

and adapted to engage the top rail of the stall when the stop bar has been swung into 25 operative position.

7. A stop bar attachment for stalls having a top rail including a clamp adapted to be secured to the top rail, a swinging arm pivotally mounted on the clamp, a stop bar secured to the swinging arm, a laterally projecting wing carried by the swinging arm, intermediate its ends, and a shift bar pivotally connected to the said wing in an off-set relation to the swinging arm.

8. A stop bar attachment for stalls having a top rail including a swinging arm, means for pivotally mounting the swinging arm on the top rail, a stop bar secured to the swinging arm, a stop lug on the swinging arm and 40 having a contact face adapted to engage the top rail to limit the swinging movement of the stop bar, and a shift bar pivotally connected to the stop lug.

In testimony whereof I affix my signature.
RUDOLPH J. LANGER.
